To all whom it may concern:

Be it known that I, Henry I. Nettle, a citizen of the United States, residing at Norwood, in the county of Norfolk and State of Massachusetts, have invented a new, original, and ornamental Design for an Addressing Machine, of which the following is a specification, reference being had to the accompanying drawings, forming a part thereof.

In the drawings:

Fig. 1 is a perspective view of the machine;
Fig. 2 is a plan view of the machine;
Fig. 3 is a side elevation of the machine;

Fig. 4 is a right hand end view of the machine;
Fig. 5 is a left hand end view of the machine.

I claim:

The ornamental design for an addressing machine, substantially as shown.
